UNITED STATES PATENT OFFICE.

HOWARD M. DUDLEY, OF PHILADELPHIA, PENNSYLVANIA.

DYEING-MACHINE.

1,280,190.

Specification of Letters Patent.

Patented Oct. 1, 1918.

Application filed October 29, 1917. Serial No. 198,920.

To all whom it may concern:

Be it known that I, HOWARD M. DUDLEY, a citizen of the United States, residing in the city of Philadelphia, county of Philadelphia, and State of Pennsylvania, have invented certain new and useful Improvements in Dyeing-Machines, of which the following is a full, clear, and exact specification.

My invention relates to dyeing machines 10 and refers particularly to machines suitable for the dyeing of textile fibers, and like materials, by means of a circulating liquid.

One object of my invention is a device whereby textile fibers, especially warp balls 15 and similar forms, may be dyed evenly and uniformly while in a compressed condition.

Another object of my invention is a device whereby a liquid may be passed uniformly and thoroughly through a series of 20 compressed masses of fiber.

Another object of my invention is a device whereby the formation of channels may be prevented while passing a liquid through a series of compressed masses of fiber.

Another object of my invention is a device whereby the condition of the treated fiber may be determined without interrupting the process of treatment.

Another object of my invention is a device comprising a testing device whereby the condition of the treated fiber may be accurately determined without opening the dyeing chamber.

These and other objects of the device of 35 my invention will be evident upon a consideration of my specification, drawings and claims.

Great difficulty is experienced in obtaining even and uniform dyeings of textile 40 fibers, especially warp balls and similar forms, in those machines in which the fiber is treated while under pressure to the action of a dyeing liquid. Under these conditions the liquid has a tendency to form channels 45 or passages through the fiber, through which more liquid passes than through other portions of the fiber, thus causing uneven results.

It is evident that when fiber is compressed 50 between two plates having openings with parallel sides, the liquid forced through the openings will be impinged in a series of liquid columns against the fiber forcing itself therethrough in a series of channels, the intermediate portions of the mass being less affected by the liquid.

It is further evident that unless the liquid pressure is absolutely equal upon all parts of the foraminous plates, more liquid will be forced through some of the holes than 60 through others causing uneven dyeings.

It is further evident that an equal liquid pressure must be maintained at all times throughout the entire mass.

My device accomplishes all of these three 65 vital elements of successful dyeing and presents a method whereby all portions of a series of fiber masses will be treated equally by the impinged liquid whereby the formation of channels is prevented, whereby the 70 liquid pressure will be absolutely equalized over the entire foraminous plate and whereby a uniform liquid pressure will be maintained throughout the fiber masses.

In order to equalize the liquid pressure 75 over the entire foraminous plate, I pass the liquid into a chamber containing a series of baffle plates distributed below the foraminous plate, thus distributing the liquid as evenly as possible; from this chamber the 80 liquid passes through a foraminous plate, thus breaking up any currents that have been formed, into a chamber from which it passes through a series of foraminous plates into the fiber masses. This chamber be- 85 tween the two sets of foraminous plates causes a complete equalization of the liquid pressure and allows an absolutely uniform and equal amount of liquid to pass through all portions of the fiber masses. 90

In order to prevent the formation of channels through the masses due to the impinging of liquid columns upon the fiber, the foraminous plates of my device upon which the fiber rests consist of a series of inwardly 95 projecting members, thus presenting a maximum of fiber surface to the action of the liquid and causing it to penetrate the masses in an equal and complete manner.

In order to maintain a uniform liquid 100 pressure throughout the entire fiber masses, the two series of foraminous plates of my device, between which the fiber is compressed, are exactly similar in construction, the exit of the liquid from the masses therefore being under the same conditions as its 105 entrance into the masses.

By means of my testing device, the condition of the dyed fiber may be determined at any time without opening the dyeing 110 chamber or interrupting the operation, the value of which device is evident.

I also provide means whereby the liquid may be passed in opposite directions through the fiber when desired.

Having thus broadly described my invention; I give the following example of one form of my device.

In the particular form of my device shown in the accompanying drawings, similar parts are designated by similar numerals:—

10 Figure 1 is a side plan view partly in cross-section, the portion in cross-section being through the line 1—1 of Fig. 2.

Fig. 2 is a cross-section through the line 2—2 of Fig. 1.

15 Fig. 3 is a cross-section through the line 3—3 of Fig. 1.

Fig. 4 is a broken detail top plan view of one of the foraminous plates.

Fig. 5 is an end view of Fig. 4.

20 Fig. 6 is a broken top plan view of one of the foraminous plates.

Fig. 7 is an end view of Fig. 6.

Fig. 8 is an enlarged cross-section of a testing device.

25 The device of my invention, as illustrated, comprises a receptacle having the side wall 20, to a series of fiber chambers, within which is a series of foraminous plates 21, 21, resting upon the annular offset 22 of the side

30 wall 20. Spaced above the plate 21, and supported therefrom by the annular member 23, is a series of foraminous plates 24, 24. The bottom 25 of the receptacle contains a series of staggered baffle plates 26, 26, 35 26. Within the extended portion 27 of the bottom 25 is a series of conduits 28, 28, 28 formed by the partition members 29, 29, 29. Removable from and slidable within the receptacle is a series of foraminous plates 30, 40 30. A removable top 31 contains a series of staggered baffle plates 32, 32 and conduits and partition members similar to those in the bottom 25. The top 31 also carries a series of foraminous plates 36, 36, and the

45 downwardly extended portions 37, 37 of the top are capable of abutment upon the plates 30, 30. Screw bolts 38, 38 passing through openings in the flange 39 of the top 31 and threaded in the holes in the flange 40 of the 50 wall 20 allow of the top being forced downwardly into the receptacle. Bolt eyes 41, 41 are inserted into the top 31 as a means for raising the top.

A testing tube, shown in cross-section in 55 Fig. 8 is similar and proportionate to the larger device and comprises the wall 42 and the foraminous plates 43, 44, 45 and 46 similar to the plates 36, 30, 24, and 21 respectively. The threaded hollow members 47 60 and 48, threaded with the interior of the wall 42 enable the compression of the fiber 101. The lower portion of the wall 42 is connected with the pipe 49 by means of the bushing 50. The pipe 49 carries the valve 65 51 and is connected with the chamber 52 by

means of the conduit 53. The upper portion of the wall 42 is connected with the pipe 54 by means of the bushing 55. The pipe 54 carries the valve 56 and is connected to the chamber 57 by the conduit 58. By 70 means of the bushings 50 and 55, the testing device can be removed from the connection with the pipes 49 and 54 to allow of charging the same or of examining the contents.

Plates 24 and 30, as shown in Figs. 4 and 75 5, consist of a series of parallel bars 60, 60, carrying inwardly extended pointed members 61, 61.

Plates 21 and 36, as shown in Fig. 6, consist of a plate having circular openings 63, 80 63 therein.

The extended top member 35 is connected to the pipe 64 by means of the flange coupling 66. The pipe 64 carries the valve 67 and is connected to the discharge chamber 85 of the pump 68 by means of the slide bushing 90.

The extended bottom member 27 is connected to the pipe 69, which carries the valve 70, and is connected to the discharge chamber 90 of the pump 68.

The pipe 71 connecting the pipes 64 and 69 carries the valves 72 and 73 and is connected with the pipe 74 emptying into the top of the reserve tank 75.

The bottom of the reserve tank 75 is connected to the pipe 76, carrying the valve 77 and connected to the receiving chamber of the pump 68. A pipe 78 carrying the valve 79 connects a dissolving tank, not shown, 100 with the receiving chamber of the pump 68. A pipe 80, carrying the valve 81 enters the bottom of the device.

The pump 68 is connected to a source of fresh water supply by means of the pipe 94 105 carrying the valve 95.

The operation of the device is as follows:—

The warp balls 100, 100 are placed within the fiber chambers and upon the plates 24, 110 24. Plates 30, 30 are then placed upon the fiber mass in the fiber chambers, and the top 31 lowered into place. The top 35 is connected to the pipe 64 by means of the coupling 66. The screw bolts 38, 38 are then 115 inserted and screwed down, the members 37, 37 pressing the plates 30, 30 inwardly until the desired pressure is obtained upon the series of fiber masses, the pipe 64 sliding into the bushing 90. The testing device is 120 charged with the fiber mass 101, and placed in position. All of the valves are closed with the exception of valves 79, 70, 51, 56 and 72, and the pump 68 started. The liquid thus passes from the dissolving tank, not 125 shown, through the pipe 78, the pump 68, the pipe 69, the conduits 28, 28, between the baffle plates 26, 26, through the plates 21, 21, the chamber 92, the plates 24, 24, the fiber chambers and the fiber 100 therein, the plates 130

30, 30, the chamber 57, the plates 36, 36 and the various members within the top 31 into the reserve tank 75. When sufficient liquid has been introduced into the reserve 5 tank, the valve 79 is closed and valve 77 opened, the liquid then having a continuous circulation in the direction mentioned above. At the same time the liquid passes upwardly 10 through the testing device and the fiber 101 therein. When it is desired to reverse the flow of the liquid, valves 70 and 72 are closed and valves 67 and 73 are opened, thus allowing the liquid to pass in a reverse direction through the device. From time to time, as 15 desired, the condition of the fiber in the testing device may be determined by closing valves 51 and 56 and removing the device as previously described. The liquid may be drained off through the pipe 80, and water 20 may be introduced for washing the fiber by means of the pipe 94 carrying the valve 95. I do not limit myself to the particular size, shape, number or arrangement of parts 25 as described and shown, all of which may be varied without going beyond the scope of my invention as described and claimed.

What I claim is:

1. In a dyeing machine, in combination, a series of fiber chambers having imperforate 30 sides; each containing a foraminous bottom plate and a foraminous top plate, means for moving the foraminous top plate with respect to the foraminous bottom plate and maintaining it in position, a foraminous plate 35 spaced below the bottom plate, a foraminous plate spaced above the top plate; and means for forcing a liquid in either direction through the series of fiber chambers.

2. In a dyeing machine, in combination, a 40 receptacle; a series of fiber chambers within the receptacle each containing two fixed foraminous bottom plates spaced from each other and two movable foraminous top plates spaced from each other, means for moving the top plates with respect to the 45 bottom plates and for maintaining them in position; a bottom to the receptacle, a top to the receptacle and means for forcing a liquid in either direction through the device.

50 3. In a dyeing machine, in combination, a receptacle; a series of fiber chambers within the receptacle each containing two fixed foraminous bottom plates spaced from each other and two movable foraminous top plates 55 spaced from each other, means for moving the top plates with respect to the bottom plates and maintaining them in position; a bottom to the receptacle, a series of conduits for the introduction of a liquid into the bottom, a top to the receptacle, a series of conduits for the introduction of a liquid into the top and means for forcing a liquid in either 60 direction through the device.

4. In a dyeing machine, in combination, a 65 receptacle; a series of fiber chambers within

the receptacle each containing two fixed foraminous bottom plates spaced from each other, and two movable foraminous top plates spaced from each other, means for moving the top plates with respect to the 70 bottom plates and for maintaining them in position; a bottom to the receptacle, a series of baffle plates within the bottom, a top to the receptacle, a series of baffle plates within the top and means for forcing a liquid 75 against the baffle plates and through the device.

5. In a dyeing machine, in combination, a receptacle; a series of fiber chambers within the receptacle each containing a foraminous 80 bottom plate having inwardly extended members and a foraminous top plate having inwardly extended members, means for moving the one plate with respect to the other and for maintaining it in position, a forami- 85 nous plate spaced below the bottom plate, a foraminous plate spaced above the top plate; and means for passing a liquid through the device in either direction.

6. In a dyeing machine, in combination, a 90 receptacle; a series of fiber chambers within the receptacle each containing a foraminous bottom plate having inwardly extended members and a foraminous top plate having inwardly extended members, means for mov- 95 ing the one plate with respect to the other and for maintaining it in position, a forami- nous plate spaced below the bottom plate, a foraminous plate spaced above the top plate; a bottom to the receptacle, a removable top 100 to the receptacle and means for passing a liquid in either direction through the device.

7. In a dyeing machine, in combination, a receptacle; a series of fiber chambers within the receptacle, each containing a forami- 105 nous bottom plate having inwardly extended members and a foraminous top plate having inwardly extended members, means for moving the one plate with respect to the other and for maintaining it in position, a foraminous 110 plate spaced below the bottom plate, a foraminous plate spaced above the top plate; a bottom to the receptacle, a series of conduits for the introduction of a liquid into the bottom, a top to the receptacle, a series 115 of conduits for the introduction of a liquid into the top and means for forcing a liquid in either direction through the device.

8. In a dyeing machine, in combination, a receptacle; a series of fiber chambers within the receptacle each containing a forami- 120 nous bottom plate having inwardly extended members and a foraminous top plate having inwardly extended members, means for moving the one plate with respect to the other and for maintaining it in position, a foraminous plate spaced below the bottom plate, a foraminous plate spaced above the top plate; a bottom to the receptacle, a se- 125 ries of baffle plates within the bottom, a top 130

to the receptacle, a series of baffle plates within the top, and means for forcing a liquid against the baffle plates and through the device.

- 5 9. In a dyeing machine, in combination, a receptacle; a series of fiber chambers within the receptacle each containing two fixed foraminous bottom plates spaced from each other and two movable foraminous top plates spaced from each other, means for moving the top plates and for maintaining them in position; a bottom to the receptacle, a top to the receptacle, a smaller testing device, exterior to the larger device, a series 10 of spaced foraminous plates within the testing device similar to those in the larger device and means for passing a liquid equally through the two devices in either direction.

10. In a dyeing machine, in combination, 20 a receptacle; a series of fiber chambers within the receptacle each containing two fixed foraminous bottom plates spaced from each other and two movable foraminous top plates spaced from each other, means for moving the top plates with respect to the bottom plates and for maintaining them in position; a bottom to the receptacle, a series of conduits for the introduction of a liquid into the bottom, a top to the receptacle, a series 25 of conduits for the introduction of a liquid into the top, a smaller testing device, exterior to the larger device, a series of spaced foraminous plates within the testing device similar to those in the larger device and 30 means for passing a liquid equally through the two devices in either direction.

11. In a dyeing machine, in combination, 35 a receptacle; a series of fiber chambers within the receptacle each containing a foraminous bottom plate having inwardly extended members and a foraminous top plate having inwardly extended members, means for moving the one plate with respect to the other and for maintaining it in position, a 40 foraminous plate spaced below the bottom plate, a foraminous plate spaced above the top plate; a smaller testing device, exterior to the larger device, a series of spaced foraminous plates within the testing device similar to those in the larger device and 45 means for passing a liquid equally through the two devices in either direction.

Copies of this patent may be obtained for five cents each, by addressing the "Commissioner of Patents, Washington, D. C."

means for passing a liquid equally through the two devices in either direction.

12. In a dyeing machine, in combination, a receptacle; a series of fiber chambers within the receptacle each containing a foraminous bottom plate having inwardly extended members and a foraminous top plate having inwardly extended members, means for moving the one plate with respect to the other and for maintaining it in position, a foraminous plate spaced below the bottom plate, a foraminous plate spaced above the top plate; a bottom to the receptacle, a series of conduits for the introduction of a liquid into the bottom, a top to the receptacle, a series of conduits for the introduction of a liquid, a smaller testing device, exterior to the larger device, a series 55 of spaced foraminous plates within the testing device similar to those in the larger device and means for passing a liquid equally through the two devices in either direction.

13. In a dyeing machine, in combination, 60 a receptacle; a series of fiber chambers within the receptacle each containing a foraminous bottom plate having inwardly extended members and a foraminous top plate having inwardly extended members, means for moving the one plate with respect to the other and for maintaining it in position, a foraminous plate spaced below the bottom plate, a foraminous plate spaced above the top plate; a bottom to the receptacle, a series of conduits for the introduction of a liquid into the bottom, a top to the receptacle, a series of conduits for the introduction of a liquid into the top, a series of 65 baffle plates within the bottom, a series of baffle plates within the top, a smaller testing device, exterior to the larger device, a series of spaced foraminous plates within the testing device similar to those in the larger device and means for passing a liquid 70 equally through the two devices in either direction.

Signed at New York city, in the county of New York and State of New York, this 15th day of October, 1917.

HOWARD M. DUDLEY.
